CLAY GUN

August F. Giese, Jr., Gary, Ind.

Application October 16, 1933, Serial No. 693,818

13 Claims. (Cl. 266—42)

My invention relates to clay gun structures or outfitts adapted particularly for plugging up tapping holes of blast furnaces to shut off the flow of molten metal therefrom.

5 Clay gun structures usually comprise a cylinder for receiving clay to be discharged, some discharge means as for example a piston operable within the cylinder to discharge the clay therefrom, and driving means for the discharging 10 means mounted on the cylinder, a nozzle extending axially from the end of the cylinder being usually provided for directing the discharged clay. Heretofore, such gun structures have been suspended from supports such as cranes, or were 15 mounted on boom structure and were bodily moved from the position away from the front of the furnace and into position over the runner trough and in alignment with the tapping hole and with the nozzle inserted into the tapping 20 hole whereafter the discharge mechanism was operated to discharge the clay from the gun into the tapping hole. Such prior clay gun outfitts in which the gun structure is transported bodily involve considerable expense in the cost and in- 25 stallation of the supporting and transporting means for the gun structure and entail consid- erable cost of inspection, repair and general upkeep.

The main object of my invention is to provide a 30 clay gun outfit in which the gun structure is stationarily mounted thereby eliminating entirely the need of costly suspending and transporting means or mechanisms. In accordance with my invention the gun structure is stationarily mounted in convenient position on the floor adjacent to but at one side of the runner trough and a nozzle structure is mounted in front of the furnace and connected with the discharge end of the stationary gun structure and operable to move 35 a nozzle end into or out of the tapping hole.

40 Another important feature of the invention resides in the arrangement of the nozzle structure and its operation and control.

The above referred to and other features of 45 the invention are shown incorporated in the structure disclosed on the drawings, in which drawings—

Figure 1 is a plan view of the gun and nozzle structure showing its location relative to a furnace;

50 Figure 2 is an enlarged side elevation of the gun structure;

Figure 3 is an enlarged front elevation of the nozzle structure and its controlling apparatus;

55 Figure 4 is an enlarged section of the nozzle

structure on plane IV—IV of Figure 1 and also showing the runner trough and part of the furnace in vertical section;

Figure 5 is an enlarged section on plane V—V of Figure 1 showing the coupling between the gun 5 and the nozzle structure;

Figure 6 is a section on plane VI—VI of Figure 5; and

Figure 7 is an end view of the structure shown 10 in Figure 5.

The gun structure shown is of the type disclosed in my Patent No. 1,852,560 issued April 5, 1932.

Briefly describing the gun structure shown, it 15 comprises a cylinder 10 mounted on a suitable supporting base 11 and having an outlet duct 12 extending from its outlet end. A cylinder head 13 is secured to the cylinder concentric therewith to form a cylinder bore for the travel of a piston 14 from which extends rearwardly a driving 20 screw 15.

A frame 16 secured to the head 13 forms there- 25 with a housing structure for the driving means for the screw. This driving means comprises a worm wheel 17 having threaded engagement with the screw and suitably journalled in the housing. A worm wheel 18 engages the screw and is mount- 30 ed on a shaft 19 journalled in the housing, a gear 20 being secured to the shaft and engaged by a transmission train 21 driven by a suitable motor 22, preferably electric. A platform 23 extending from the housing 17 serves as a support for the motor and a tubular housing 24 receives the end of the screw shaft 15. The cylinder 10 has one or more filler openings 25 which may be securely 35 closed by cover structures 26. When the electric motor is connected for operation, the worm wheel 17 will be driven and the screw shaft will be shifted to move the piston 14 slowly and power- 40 fully in the cylinder for the ejection of clay there- from.

The illustrated embodiment shows parts of the 45 front wall of a furnace F, the furnace having the tap hole 27 communicating with the runner trough 28 through which the molten metal is conducted away from the furnace. Extending transversely across the runner trough in front of the furnace is the controllable nozzle mechanism indicated as a whole by N. This nozzle structure comprises a supporting body 29 which is shown as being tubular and having a contracted or neck end 30 in which is secured a shaft 31 having bearing 50 in a pedestal 32 supported on the floor 33 in front of the furnace. Adjacent to the bearing pedestal is a gear housing structure 34 also mount- 55

ed on the floor 33 and journalling the outer end of the shaft 31. Within the housing a worm wheel 35 is secured to the shaft and below the worm gear a worm shaft 36 is journalled in the housing and 5 carries a worm 37 meshing with the worm wheel. A suitable motor 38, preferably electric, is mounted on the floor and connected with the worm shaft 36. A suitable drive coupling 39 may be interposed in the shaft 31 between the bearing 10 pedestal 32 and the gear housing 34.

A discharge or nozzle tube T extends downwardly from the supporting body 29 and has the upper bend or elbow 40 extending through a recess 41 cut in the supporting body 29 so that 15 the upper end of the elbow is coaxial with the body 29 and the shaft 31 and the axis of the lower end of the bend is in a vertical plane. At its lower end the discharge or nozzle tube T terminates in an elbow or bend 42 to which is secured the nozzle fitting 43 which as shown is of conical shape. The axis of the discharge or nozzle tube T depending from the supporting body 29 is in the vertical plane extending through the runner trough and the tapping hole 27 so that upon revolving of the supporting body 29 this nozzle 20 structure may be swung upwardly into a position away from the tap hole and runner trough, as indicated by dotted lines in Figure 4, or into its lower or discharging position with the nozzle end 25 43 projected into the tapping hole as shown in full lines in Figure 4.

The nozzle structure T at its outer end is coupled to the discharge end of the cylinder of the gun structure by bearing structure receiving 35 the end of the nozzle structure. As best shown in Figures 5, 6 and 7, the outer end of the nozzle tube terminates in a flange fitting 44 which may be integral with the discharge tube but is preferably a separate member secured to the nozzle 40 tube as by means of a welding as indicated at 45. On account of the irregular shape of the discharge tube T the flange fitting can be more readily made as a separate part.

The gun structure from which the clay is fed 45 to the nozzle structure may be mounted in any convenient position in front of the furnace. As shown, it is secured on the floor 33 at one side of the runner trough and inclined away therefrom so as to leave plenty of room for access to the 50 runner trough and tap hole. The discharge end 12 of the gun structure is connected by tubing with the inlet end of the nozzle tube T and preferably this tubing is composed of stock parts welded together. As shown, the tubing comprises 55 a straight cylindrical section 46 secured to the gun discharge end 12, bend sections 47 and 48 and an end straight cylindrical section 49 which end section is coaxial with the flange 44 and the outer end of the nozzle tube T, these various sections 60 being welded together as indicated at 50.

The end cylindrical tube section 49 extends through an opening 51 in the vertical wall 52 of a supporting pedestal 53 mounted on the floor 33 adjacent to the runner trough, the tube being 65 rigidly secured to the wall 52 as by welding indicated at 54. Surrounding the tube end 49 concentric therewith and abutting the wall 52 is a cylindrical annular wall 55 engaged at its outer end by an annular plate 56, bolts 57 extending 70 through the end plate, the annular wall 55, and the pedestal wall 52 to secure these parts together to form a cylindrical enclosing chamber 58. The flange 44' at the outer end of the flange fitting 44 extends into the chamber 58 through the opening 75 in the end wall 56, the circumferential sur-

face of the flange engaging the inner surface of the annular wall 55, the flange also receiving and bearing on the outer end of the tube section 49 to form a joint therewith, so that clay ejected from the clay gun structure may be directed into the nozzle tube T to be conducted through the nozzle fitting 43 into the tap hole. Such passage of the clay under powerful pressure and impetus from the clay gun will subject the conducting tubing and nozzle tubing to considerable tension stress. 10 The end plate 56 forms an abutment for the inner wall or shoulder of the flange 44' and prevents axial separation of the flange fitting and the tube 14. Preferably an abutment ring 59 is interposed between the flange shoulder and the end 15 wall 56 and this ring is preferably of some bearing metal, such as brass or bronze, to withstand axial stress and also to offer a less resistant bearing surface so that the nozzle structure may be more readily swung into operative or inoperative position. 20

As shown, the end wall 56 instead of being one integral piece may be of two semi-circular pieces as shown in Figure 7, and the bearing ring 59 may also be of two semi-circular pieces. The plane 25 of the joint 60 of the sections of the wall 56 is preferably at right angles to the plane of the joint 61 of the bearing ring parts, as clearly shown in Fig. 7. The sections of the end wall 56 may have lateral projections thereon to form an 30 aligning and abutment flange 62 for the bearing ring 59.

To guard against leakage of clay through the joint between the flange fitting and the tube end 49 suitable packing is provided. As shown, the 35 flange 44' has the inner annular recess 63 for receiving packing material 64 which is held in place and compressed by a packing ring or gland 65 secured by suitable bolts 66. The annular wall 55 is provided with openings 67 through 40 which access may readily be had to the bolts 66 for adjustment of the packing means.

Briefly describing the operation, the clay gun 45 is filled with clay and the motor 38 is put into operation to cause rotation of the nozzle structure N to swing the nozzle tube T downwardly into the runner trough with the nozzle end 43 projected into the tapping hole 27. The motor 22 on the gun structure is then started and the clay is slowly and powerfully ejected from the gun 50 cylinder and caused to flow through the connecting tubing and into and through the nozzle tube T for discharge from the nozzle end 43 into the tapping hole. After the tapping hole has been 55 filled the motor 38 is operated to rotate the nozzle structure N to swing the nozzle tube T back to its upper position away from the runner trough and the tapping hole where it will be out of the way of the workmen.

Instead of the electrically driven screw shaft 60 type of clay gun shown, other types of guns may be used and provided they are capable of delivering sufficient pressure to force the clay through the conducting tubing against the resistance encountered at the various bends. The type of gun shown may be comparatively small and compact and still efficiently readily propel sufficient volume of clay for a tap hole plugging operation without refilling of the gun. 65

By the use of my improved arrangement, involving the stationarily mounted clay gun structure, all additional gun supporting and transporting mechanism heretofore necessary with bodily movable gun structures has been eliminated. 70 75

ed with a corresponding saving in cost, supervision and maintenance.

I have described a practical and efficient embodiment of the various features of my invention, but I do not desire to be limited to the exact construction, arrangement and operation shown and described as changes and modifications may be made without departing from the scope of the invention as outlined in the accompanying claims.

10 I claim as follows:

1. Mechanism for plugging the tapping hole of a furnace comprising a cylinder permanently mounted in a fixed position and provided with means for discharging clay therefrom, a discharge nozzle structure connected with said cylinder to receive the clay therefrom, and means for moving said nozzle independently of said cylinder into or out of the furnace tapping opening.

2. Apparatus for plugging the tapping hole of a blast furnace comprising a cylinder having means for discharging clay therefrom under heavy pressure, a discharge nozzle structure connected with the cylinder to receive the clay therefrom, and means for moving said nozzle structure relative to said cylinder into and out of communication with a furnace tapping hole.

3. In apparatus for plugging the tapping hole of a blast furnace, the combination of a clay gun cylinder permanently mounted in a fixed position near the tapping hole and provided with means for discharging clay therefrom under heavy pressure, a discharge nozzle structure adjacent to the tapping hole and connected with the cylinder to receive the clay therefrom, and means for rotating said nozzle structure independently of the cylinder into or out of communication with a tapping hole with which it is associated.

4. The combination with a blast furnace having a tapping hole, of a clay gun cylinder structure mounted in front of the furnace in a permanent fixed position, and a nozzle structure for said cylinder structure movable relative thereto away from the tapping hole or into communication therewith.

45 5. Clay discharging apparatus for the tapping hole of a furnace comprising a stationarily mounted clay gun cylinder provided with means for discharging clay under heavy pressure and having a discharge duct terminating above and at one side of the tapping hole, and a discharge nozzle jointed to the end of said duct and movable in a vertical plane away from the tapping hole or into communication therewith.

55 6. Clay discharging structure for a furnace having a tapping hole and a runner trough extending therefrom, said structure comprising a clay gun cylinder permanently mounted in a fixed position at one side of the runner trough and having a discharge duct terminating adjacent to the end of said tapping hole, a discharge nozzle jointed to the end of said discharge duct for independent rotation on an axis at right angles with the runner trough, and means for swinging said nozzle into position above the runner trough or into said runner trough into communication with the tapping hole.

7. Clay discharging structure for a blast furnace having a tapping hole and a runner trough extending therefrom, said structure comprising a clay gun cylinder permanently mounted in a fixed position at one side of the runner trough, and having a discharge duct terminating above and at one side of the tapping hole, a supporting shaft structure extending across the runner trough at

right angles therewith and above the tapping hole, and a discharge nozzle supported on said shaft structure and jointed to said discharge duct, and means for rotating said shaft structure to move said discharge nozzle out of the runner trough or into the runner trough in communication with the tapping hole.

5 8. A clay gun comprising a cylinder provided with clay discharging means and having a discharge duct, and a discharge nozzle connected with said duct and adapted to be independently swung away from or into clay discharging position.

9. A clay gun comprising a cylinder provided with clay discharging means and having a discharge duct terminating in a bearing head, and a discharge nozzle having bearing at one end in said head for independent swinging movement into or out of clay discharging position.

10 10. A clay gun for plugging the tapping hole of a blast furnace, said gun comprising a cylinder structure permanently mounted in a fixed position in front of the furnace and provided with clay discharging means and having a discharge duct terminating adjacent to the furnace tapping hole, a bearing coupling head at the end of said duct with its axis above the tap hole, a discharge nozzle coupled at its outer end to and having bearing in said head, and means for independently rotating said discharge nozzle to swing it away from the tapping hole or into position with its lower discharge end in communication with the tapping hole.

15 11. Clay discharging structure for plugging the tapping hole of a furnace, said structure comprising a cylinder permanently mounted in a fixed position in front of a furnace at one side of the tapping hole and provided with clay discharging means and having a discharge duct secured thereto and terminating adjacent to and above the tapping hole, a discharge nozzle having bearing coupling engagement with said discharge duct for swinging away from the tapping hole or into a discharge position relative thereto, and power driven means for controlling the swing of said discharge nozzle.

20 12. The combination with a blast furnace having a tapping hole, of a clay gun cylinder immovably fixed to the floor in front of the furnace and provided with clay discharging means, and a discharge nozzle structure for said cylinder movable independently thereof away from or into communication with the tapping hole.

25 13. A clay discharging outfit for plugging the tapping hole of a blast furnace having a runner trough extending from the tapping hole, said outfit comprising a cylinder permanently mounted in a fixed position at one side of the runner trough, a supporting shaft structure extending across the runner trough above the tapping hole, said cylinder provided with clay discharging means and having a discharge duct secured thereto and terminating in alignment with the axis of said shaft structure, a discharge nozzle structure supported on said shaft structure, a joint bearing connecting the end of said nozzle structure with the cylinder discharge duct, said nozzle structure being aligned with the runner trough, and power means for rotating said shaft structure to cause swing of said nozzle structure out of the runner trough or into discharge position relative to the tapping hole.

30 AUGUST F. GIESE, JR.
